(57) **CLAIM**

The ornamental design for an electronic device as shown and described.

DESCRIPTION

FIG. 1 is a front top perspective view of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

(Continued)

FIG. 7 is a bottom view thereof; and,
 FIG. 8 is an enlargement taken from FIG. 1 thereof.
 The broken lines depict portions of the electronic device
 which form no part of the claimed design.
 The shading on the key array represents the color black or
 color contrast.
 In FIGS. 1-6, the plurality of circles to the left and right of
 the keyboard are shown in broken lines.
 The dot-dash broken lines show an area of enlargement.
 The white wire-frame lines on the keys are provided with the
 sole purpose of clearly defining and describing the character
 of the dark surfaces, and do not depict the color white or
 surface ornamentation.
